CLAIM

(21) Appl. No.: **29/160,135**

The ornamental design for a handle of a string cutter for cutting the silica gel of the glass, as shown and described.

(22) Filed: **May 7, 2002**

DESCRIPTION

(51) LOC (7) Cl. **08-05**

FIG. 1 is a front-right-top perspective view of a handle of a string cutter for cutting the silica gel of the glass, showing my new design;

(52) U.S. Cl. **D8/107; D8/98**

FIG. 2 is a front elevational view thereof;

(58) Field of Search D8/14, 95, 96, D8/97, 98, 107; 30/166.3, 517, 116; 83/830

FIG. 3 is a rear elevational view thereof;

(56) **References Cited**

FIG. 4 is a left side elevational view thereof;

U.S. PATENT DOCUMENTS

FIG. 5 is a right side elevational view thereof;
